D. F. DYKE,
ADJUSTABLE BACK FOR SOFA BEDS,
APPLICATION FILED NOV. 16, 1916.
1,260,348. Patented Mar. 26, 1918.

UNITED STATES PATENT OFFICE.

DARRELL F. DYKE, OF CHICAGO, ILLINOIS, ASSIGNOR TO THE SENG COMPANY, OF CHICAGO, ILLINOIS, A CORPORATION OF ILLINOIS.

ADJUSTABLE BACK FOR SOFA-BEDS.

1,260,348.

Specification of Letters Patent. Patented Mar. 26, 1918.

Application filed November 16, 1916. Serial No. 131,630.

To all whom it may concern:

Be it known that I, DARRELL F. DYKE, a citizen of the United States, residing at Chicago, in the county of Cook and State 5 of Illinois, have invented a new and useful Adjustable Back for Sofa-Beds, of which the following is a specification.

My invention relates to improvements in adjustable backs for sofa-beds of that class 10 wherein to adjust the bed to operative position it is first necessary to turn the seat, and to permit of the latter operation, to elevate the back, whereby to release the seat from its engagement with the back.

15 The principal objects of the invention are to provide a simple as well as economical mechanism for connecting the sofa-back to the sofa-frame, whereby said back may be raised and lowered with comparatively little effort and when raised will automatically remain in such position.

20 Other objects and advantages of the invention will hereinafter appear, and the novel features thereof will be particularly 25 pointed out in the appended claims.

Referring to the drawing:

Figure 1 is a front elevation of a sofa-bed embodying the invention, the back being 30 illustrated in its raised position and shown partly broken away at one end to expose the mechanism covered thereby.

Fig. 2 is an enlarged vertical transverse 35 sectional view, parts being broken away, and the back shown elevated.

40 Figs. 3 and 4 are side and bottom views, respectively, of a detail of construction hereinafter referred to.

Similar numerals of reference indicate 45 similar parts in all the figures of the drawing.

To illustrate the application and operation of the invention, I have shown the same in connection with the conventional form of sofa-bed, or rather, so much thereof as is necessary. The frame-work, as is usual 50 in this type of bed, comprises the opposite ends 1, the connecting back-portion 2, and the overturning or forwardly swinging seat 3, the frame, in this instance, having one or 55 more standards 4, projecting upwardly from its rear edge, between which and the seat 3, rests the lower edge of the adjustable sofa-back 5, when the latter is lowered and the structure is in what might be termed "sofa-form," (see dotted lines, Fig. 2.)

To each end of the sofa-back 5, preferably

at the outer sides of the vertical end-bars thereof, is secured by ordinary screws, a metal securing-plate 6, the same being located adjacent the lower edge of the back 5. Pivoted to the upper ends of each of such plates 6, as indicated at 7, is an elbow-lever 8, at the lower bent end of which is located a laterally disposed pintle 9. Similarly pivoted, as at 10, to the lower end of each of the plates 6, is a bell-crank lever 11, the upper end of which is angularly disposed, as at 12, the two levers at each side of the sofa-back being oppositely disposed.

Bolted to the underside of the usual cross-piece of the sofa-frame, (which cross-piece I have indicated as 13,) near each end of the same, is an angular sheet-metal bracket 14, (see detail Figs. 3 and 4,) and each comprises an upper securing portion 15, the front 75 end of which is downwardly disposed to form a slightly inclined spring-buffer 16, and a depending side flange 17. The securing portion 15, is provided with ordinary screw-receiving holes, and the side flange 80 with a hole 19, the hole 19 of each bracket being for the purpose of receiving the pintle 9 of the adjacent levers or links 8.

Preferably angular sheet-metal brackets 20, are located vertically below the brackets 14 and project somewhat beyond the latter. To the brackets 20, the bell-crank levers 11 are pivoted, as at 21, the points of pivot being coincident with the angles of the levers.

A coiled spring 22, may have its upper end connected with the end of that branch or member of the bell-crank opposite that pivoted to the sofa-back, the lower end of the spring being made fast to an eye 23, conveniently located in the back 2 of the frame.

It will be seen that the springs 22 are so located with relation to the pivots 21, which are the fulcrums of the bell-crank levers 11, that as said levers 11 are moved on their fulcrums, the springs will pass to one side only 90 of said fulcrums, and when this occurs the levers 11 will be upwardly disposed and the sofa-back raised or elevated to its uppermost position, the springs combining to maintain these parts thus. When, however, the sofa-back is lowered to the position shown in dotted lines (Fig. 2,) the springs will be under somewhat greater tension, but being in substantial alinement with the pivots 21, will exert little if any influence. They are, however, in such position that the slightest upward movement of the sofa-back will

serve to carry the springs rearward and beyond the fulcrums 21 of the bell-crank levers and thus cause them to combine and aid in the elevation of the sofa-back. Of course, 5 in lowering the back, the weight of the latter, to a certain extent, counterbalances the strength and tendency of the springs, the one about counterbalancing the other. Thus it will be apparent that but slight exertion 10 is necessary in either the lowering or raising operation of the sofa-back and that the latter may be easily and noiselessly accomplished.

An arrangement of links and levers, combined with suitable springs, will be found 15 very useful in that class of sofa-beds to which I have referred, as their presence will greatly reduce the labor now necessary in operating the bed to open and closed positions. Moreover, by the employment of the bell-crank levers 11, it will be seen that the springs exert the greatest leverage when the sofa-back is wholly raised, so that no further means is required for locking or holding the 20 back thus elevated and while the bed is in use as such. It will be understood that I have merely herein typified my invention, and that there are other arrangements of levers and links that will accomplish similar 25 results, and I do not desire to be understood as limiting my invention to the exact details described and illustrated.

So, also, as to the forms and constructions 30 of brackets employed for connecting the links and levers to the sofa-frame. The bracket embodying the spring-buffer 16 will be found useful and beneficial, the spring-buffer serving the purpose of cushioning and deadening the noise of closing 35 the back, but, as will be apparent, other forms of brackets may be used. The standards 4 will be found useful as stops for the back when lowered, and for this purpose, combine with the bumpers 16.

40 Having described my invention, what I claim, is:

1. In a sofa-bed, comprising a movable seat, the combination with a sofa-frame having a back provided with an overhanging 45 top rail, of a vertically movable sofa-back, a pair of upper links pivoted at their outer ends to the opposite ends of the back and having their inner ends angularly disposed to their remaining portions and pivoted to the back of the sofa-frame below the overhanging top-rail, whereby the latter is cleared when the movable back is elevated, a pair of lower links pivoted at their outer ends to the opposite ends of the back and 50 at their inner ends to the back of the sofa-frame, and means for retaining the back in either its raised or lowered position.

2. In a sofa-bed, comprising a movable

seat, the combination with the sofa-frame having a back provided with an overhanging top-rail, of a vertically movable sofa-back, a pair of upper links pivoted at their outer ends to the opposite ends of the back and having their inner ends angularly disposed to their remaining portions and pivoted to the back of the sofa-frame below the overhanging top-rail, whereby the latter is cleared when the movable back is elevated, a pair of lower bell-crank levers pivoted at their outer ends to the movable back 70 and at their angles to the sofa-frame, and counterbalancing springs connected to the bell-crank levers at the inner ends of the latter and to the sofa-frame and so positioned with relation to the pivot points between the angles of the bell-crank levers and the sofa-frame as to be placed under tension when the movable back is lowered and to aid in raising the latter after an initial movement of the same. 85

3. In a sofa-bed, comprising a movable seat, the combination with the frame, of a vertically movable sofa-back, links pivoted to the ends of the back and at their inner ends to the sofa-frame, bell-crank levers 90 pivoted at their inner ends to the back below the points of pivot of the links, and having their fulcrum points located at their angles, and counterbalancing springs connected to the opposite ends of said bell-crank levers and adapted to counterbalance the weight of the sofa-back and so positioned with relation to said fulcrum points as to be substantially in line therewith when the back is lowered and at one side of said 100 points when the back is elevated, whereby the back is held in such elevated position.

4. In a sofa-bed, comprising a movable back, the combination with the main-frame, of a vertically movable back, a pair of links pivoted to the ends of the movable back, angular sheet-metal brackets having laterally disposed openings and forwardly and downwardly disposed extensions forming spring-buffers, pintles connecting the rear 110 ends of the links and said openings of the brackets, a pair of bent bell-crank levers pivoted at their bent ends to the ends of the back below the links, brackets extending from the main-frame and upon which 115 the bell-cranks are fulcrumed, and a pair of counterbalancing springs connected to the main-frame and at their opposite ends to the rear free ends of the bell-cranks.

In testimony whereof I have signed my 120 name to this specification in the presence of two subscribing witnesses.

DARRELL F. DYKE.
